Primary Examiner — Jonathan J Han(74) *Attorney, Agent, or Firm* — Murray, Ziel &
Johnston; Aaron Powell(57) **CLAIM**

The ornamental design for a penny loafer, as shown and described.

DESCRIPTION

FIG. 1 is a top, front, left side perspective view of a penny loafer, showing my new design;

FIG. 2 is a bottom, rear, right side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of portion “9” in FIG. 2; and,
FIG. 10 is an enlarged view of portion “10” in FIG. 2.

The evenly dashed broken lines depict portions of the penny loafer that form no part of the claimed design. The unevenly dashed broken lines define the boundaries of the enlarged views and form no part of the claimed design.
